ABSTRACT

A toothbrush drying device comprises a housing having toothbrush accommodating means therein and a removable cover. A heater in the housing heats the air in the housing thereby drying toothbrushes in the housing. A selectively adjustable control device coupled to the heater controls the duration of heating. A source of ultraviolet light in the housing in proximity with the toothbrush accommodating means destroys bacteria on toothbrushes in the housing.

TOOTHBRUSH DRYING DEVICE

DESCRIPTION OF THE INVENTION

The present invention relates to a toothbrush drying device.

The principal object of the invention is to provide toothbrush drying device of simple structure for drying toothbrushes and destroying bacteria thereon with efficiency, effectiveness and reliability.

In order that the invention may be readily carried into effect, it will now be described with reference to the accompanying drawing, wherein:

FIG. 1 is a partly cutaway, partly sectional view of an embodiment of the toothbrush drying device of the invention; and

FIG. 2 is a view, partly in section, taken along the lines 2 — 2, of FIG. 1.

In the Figures, the same components are identified by the same reference numerals.

The toothbrush drying device of the invention comprises a housing 1 (FIGS. 1 and 2) having toothbrush accommodating racks 2, 3 and 4 (FIG. 2) therein and a removable cover 5 (FIG. 1).

A heater (FIG. 1) in the housing 1 heats the air in the housing thereby drying toothbrushes 6 and 7 (FIG. 1) in the housing. The heater comprises a heater 8 (FIG. 1) for heating ambient air, a fan 9 (FIG. 1) for circulating air through the heater into the housing and a motor 10 (FIG. 1) for driving the fan.

A selectively adjustable control device is coupled to the heater 8, 9, 10 and controls the duration of heating. The control device comprises a timer 11 (FIG. 1) coupled to and controlling the operation of the motor 10 and a manually operated switch 12 (FIG. 1) coupled to

the timer for setting the time of operation of the motor to a desired period.

A source 13 (FIG. 1) of ultraviolet light is provided in the housing 1 in proximity with the toothbrush accommodating racks 2, 3 and 4 and functions to destroy bacteria on toothbrushes 6 and 7 in the housing.

While the invention has been described by means of a specific example and in a specific embodiment, I do not wish to be limited thereto, for obvious modifications will occur to those skilled in the art without departing from the spirit and scope of the invention.

I claim:

1. A toothbrush drying device, comprising a housing having toothbrush accommodating means therein and a removable cover; heating means in the housing for heating the air in the housing thereby drying toothbrushes in the housing; selectively adjustable control means coupled to the heating means for controlling the duration of heating; and a source of ultraviolet light in the housing in proximity with the toothbrush accommodating means for destroying bacteria on toothbrushes in the housing.

2. A toothbrush drying device as claimed in claim 1, wherein the heating means comprises a heater for heating ambient air, a fan for circulating air through the heater into the housing and a motor for driving the fan, and the control means comprises a timer coupled to and controlling the operation of the motor and switch means coupled to the timer for setting the time of operation of the motor to a desired period.
